UNITED STATES PATENT OFFICE.

CHARLES HAMILTON PAJEAU, OF EVANSTON, ILLINOIS.

MECHANICAL-CONSTRUCTION BLOCKS.

1,092,591.

Specification of Letters Patent. Patented Apr. 7, 1914.

Application filed January 6, 1913. Serial No. 740,430.

To all whom it may concern:

Be it known that I, CHARLES HAMILTON PAJEAU, citizen of the United States, residing at Evanston, in the county of Cook 5 and State of Illinois, have invented certain new and useful Improvements in Mechanical-Construction Blocks; and I do hereby declare the following to be a full, clear, and exact description of the invention, such as 10 will enable others skilled in the art to which it appertains to make and use the same.

My invention relates to mechanical construction blocks and particularly to the class of blocks used for erecting toy buildings, 15 bridges, furniture and other structures.

The object of my invention is to provide a set of such blocks in which the constituent members will be relatively and interchangeably interfitting or coacting and in 20 which part of these members will be adapted to interchange to form a container for housing the balance of the set. I attain this object by the construction shown in the accompanying drawings, in which—

Figure —1— is a plan view of a set of blocks embodying my invention, part of the blocks comprising the cover of a container being cut away to expose others. Figs. 25 —2—, —3— and —4— are elevations of 20 structures formed of part of the blocks in Fig. —1—. Figs. —5—, —6— and —7— are sections through Fig. —1— along the lines 5—5, 6—6 and 7—7. Fig. —8— is a fragmentary view of a corner of the frame 25 portions of the set, with one member slid out of its normal alinement.

In the drawings, Fig. —1— shows part of the set of blocks as housed in a container formed of interengaged wood blocks comprising sides 1, ends 2, top members 3 and bottom members 4. Each of the members 1 preferably has near its ends dovetail shaped grooves 5 adapted to receive the dovetailed ends 6 of the end members 2; 45 the ends 6 preferably having slots 7 parallel to their faces, thereby forming slotted ends which may be manually sprung toward each other for easier insertion in the grooves 5. Each slot 7 is preferably enlarged at one 50 point into a perforation 8, into which a wedge or pin may be inserted to spread the split end 6 into locking engagement with the sides of the groove 5. The end members 2 are of the same height or width as the 55 members 1 so that when engaged with the latter the longitudinal edges of said respec-

tive members may be brought flush with each other. Each of the side members 1 also is provided with interfitting means for interengaging with other blocks of the set, 60 such as the longitudinal grooves 10 and 11 into which the ends of bottom members 4 and top members 3 respectively, may be slidably inserted. In assembling the parts 1, 2, 3 and 4, which constitute the container 65 for the remaining blocks of the set, the end members 2 and side members 1 are first slidably interengaged to form a frame, one of the end members being slid out of edge-wise alinement with the side members so 70 as to expose the ends of one of the longitudinal grooves in each of the said side members, as shown in Fig. —8—. Then the bottom members are slid into their normal position in the said grooves, after which the 75 unaligned end member of the frame is slid into its normal position to complete the open container for receiving other blocks of the set. After these have been inserted, one of the end members of the frame is again slid 80 out of alinement with the sides of the frame so as to provide access to the ends of the longitudinal grooves 11, into which the ends 85 of the cover members 3 are then slidably inserted, after which the said unaligned end member is returned to its normal alined position. By making the dovetail shaped grooves 5 upon the sides 1 slightly narrower than the dovetailed ends 6 of the end members 2, these ends 6 will spring outwardly 90 so as to engage the coacting dovetailed portions of the sides 1 with sufficient firmness for retaining the end members in either of their said alined or unaligned positions relative to the side members.

In the embodiment of my invention shown in the drawings, the set of blocks is composed partly of substantially cylindrical or dowel-shaped blocks 12 and partly of non-cylindrical blocks, the latter having perforations 13 for interfitting with the ends of the cylindrical blocks, thereby increasing the variety of structures into which component members of the set may be combined. The non-cylindrical blocks comprising the knock-down container or casing are preferably of such size as to snugly house the remainder of the set and the perforations. The perforations 13 may be either longitudinal of the blocks 3 and 4, as in Fig. —6—, or transversely of the same, as in Fig. —7—.

It will be obvious from Figs. —1— and

—8— that by manually compressing each of the split ends of the end member 2, the latter can be freely slid transversely of the side members of the frame so as to be moved into or out of edgewise alinement with the latter; also, that when the manual pressure is released, the resiliency of the split ends will cause the latter to spring outwardly so as to lock the end members 2 in rigid relation to the other members of the container. When the end member which was slid out of its normal alinement with adjacent members of the frame for permitting the insertion of the top members has been returned to its alined position (as shown as the lower edge of Fig. —1—), this end member serves to retain the slideable bottom and top members in their coacting position as parts of the container. Thus the resilient split ends of the end members form manually releasable means for interlocking these end members with other portions of the frame in such relation as to retain the other container members in rigid coaction.

While I have shown my invention in an embodiment having a particular form of releasable interlocking means and particular shapes of relatively interfitting blocks. I do not wish to be limited to these, as the various elements of my invention might be varied considerably without departing from its spirit. Neither do I wish to be limited to wood as a material for such construction blocks, although my invention is particularly adapted for utilizing the waste of wood-working establishments.

I claim as my invention:

1. A set of mechanical construction blocks comprising a plurality of blocks of various shapes and sizes adapted to be interengaged with and superposed upon each other to form structures of various architectural and mechanical forms, a number of said blocks provided with relatively interfitting and interlocking means and adapted, when inter-

engaged, to form a container for the remainder of said blocks.

2. A set of separable mechanical construction blocks of various shapes and sizes adapted to be interengaged with and superposed upon each other to provide various architectural and mechanical structures, said set including four members provided with interfitting interlocking means and adapted when interengaged to form a rectangular frame, and others of said blocks adapted to enter grooves in two opposed frame members to form a bottom and cover for said frame, whereby a container for the remainder of said set is formed.

3. A set of mechanical construction blocks comprising a knockdown container consisting of a plurality of separable relatively interfitting, interengaging and interlocking members, and a plurality of blocks of various shapes and sizes adapted to be received in said container, said blocks comprising said container being adapted, when separated and disengaged to be engaged with and superposed upon each other and the remainder of the set to produce a variety of architectural and mechanical structures.

4. A set of mechanical construction blocks including two pairs of members adapted to be interengaged to form a rectangular frame, one pair of said members having parallel transverse dovetail grooves in their opposed faces, the ends of the other pair of said members having dovetail ends of greater width than said grooves and being longitudinally slotted inwardly of said dovetail ends to render the latter contractible to fit and yieldingly engage in said dovetail grooves.

In testimony whereof I have signed my name in presence of two subscribing witnesses.

CHARLES HAMILTON PAJEAU.
